UNITED STATES PATENT OFFICE.

THOMAS S. WALLER, OF DETROIT, MICHIGAN, ASSIGNOR TO DIAMOND POWER SPECIALTY COMPANY, OF DETROIT, MICHIGAN, A CORPORATION OF MICHIGAN.

BLOWER FOR BOILERS.

1,060,800.

Specification of Letters Patent.

Patented May 6, 1913.

Application filed February 14, 1912. Serial No. 677,546.

To all whom it may concern:

Be it known that I, THOMAS S. WALLER, a citizen of the United States of America, residing at Detroit, in the county of Wayne and State of Michigan, have invented certain new and useful Improvements in Blowers for Boilers, of which the following is a specification, reference being had therein to the accompanying drawings.

This invention relates to improvements in blowers for boilers and more particularly to a construction especially adapted for vertical-tube boilers.

The object of the invention is to provide a fixed blower for this type of boiler which is so positioned and articulated that it may be readily inserted through and withdrawn from the openings commonly provided in the boiler setting and which is so constructed as to blow over part of the boiler and may be quickly and easily manipulated.

A further object of the invention is to provide such a device with certain other new and useful features, the invention consisting in the matters hereinafter set forth and more particularly pointed out in the claims, reference being had to the accompanying drawings in which—

Figure 1 is a side elevation of a boiler setting showing a blower embodying the invention in place thereon, parts of the setting being broken away to show the construction; Fig. 2 is a transverse section, substantially upon the line $x-x$ of Fig. 1; Fig. 3 is an enlarged detail of a hanging nozzle construction; Fig. 4 is an enlarged detail of an extensible nozzle construction detached from the boiler setting and shown partially in section; Fig. 5 is a further enlarged detail of a portion of the hanging nozzle detached and with parts broken away to show the construction; Fig. 6 is a view of the same at right angles to that of Fig. 5 and with parts broken away to show the construction; and Fig. 7 is a detail of a brace for said hanging nozzle.

In the drawings, 1 is the circular vertical wall of a boiler setting which, in the construction shown, is provided with clean out doors or openings 2 in the side thereof at the top of the mud drum 3 of the boiler. The water tubes 4 of the boiler extend vertically upward from this drum and to remove the accumulation of soot or other products of

combustion from the top of the drum between these tubes and from the lower ends of the tubes themselves a steam nozzle is provided which may be projected through either of the openings 2 at either side of the transverse baffle wall 5 which divides the space within the boiler setting into two chambers in the usual manner. A steam supply pipe 6 is supported in a vertical position at one side of the wall 1 and is connected with a boiler or other suitable supply of fluid under pressure, to conduct the same to a point near said openings 2 where said pipe is provided with a fitting or swivel connection 7 adapted to turn thereon about the axis of said pipe for connecting thereto a tube section 8 which is attached to said swivel fitting by a lateral branch 9 and elbow, so that said tube is free to swing upon an axis extending at right angles to the longitudinal axis of said pipe, downward in front of one of said openings. A section tube 11 is connected to the lower end of the section 8 by means of a lateral branch 12 and elbows so that said tube 11 may be turned thoroughly to said tube 8 upon an axis extending transversely to the tube and brought into parallelism therewith alongside thereof or projected to extend through the opening 2 in the wall of the boiler setting. An extension tube 13 slides freely within the section 11 to be projected therefrom by the action of the steam, and a stuffing box 14 on the end of the section forms a tight joint to prevent the escape of steam around said telescoping extension tube. When not in use this projectable nozzle is folded alongside the wall of the boiler setting in the manner shown in Fig. 1, with the two sections lying side-by side and the extension tube retracted. When it is desired to use the nozzle it is swung outwardly, turning upon the lateral pipe 9 and the section 11 then turned downward and projected through the opening 2 in the wall. Steam is then turned on by means of a valve 15 in the section 11 and the force of the steam rushing into the said section will project the extension 13 across the drum 3 of the boiler and blow all accumulation of soot therefrom. The section 11 is then retracted from the opening and the nozzle turned on the swivel 7 to bring the sections 8 and 11 opposite the opening 2 at the other side of the baffle wall 5. The soot

is then blown from the top of the drum at this side of the wall by a like manipulation of the nozzle.

In a boiler setting where there are no clean out doors opposite the top of the mud drum as where there is a bank of boilers placed side by side, the tubes and the top of the drum may be blown by means of a hanging nozzle, which is projected through openings 16 and 17 in the front and rear sides respectively of the wall above the top of the fire arch 18 covering the fire chamber which opens into the forward side of the boiler setting. Steam is supplied to this nozzle through a branch pipe 19 leading laterally from the supply pipe 6 and around to the forward side of the setting above the opening. This supply pipe 19 leads into the lower end of a casing 20 and leading laterally from this casing is a short branch 21 having a swiveled connection with the casing to turn upon its longitudinal axis. A tube section 22 is connected to the short section 21 by an elbow and extends downward at right angles thereto to swing upon the axis of the section 21. At its lower end the section 22 is bent laterally and to this laterally bent end a tubular section 23 is attached by means of a swivel head 24 and extends parallel with the line of the section 22. The extreme lower end of the section 23 is provided with a head 24 having an end wall 25 formed with an opening to receive a rotatable jet nozzle 26. The wall 25 is formed at an angle to the longitudinal axis of the tube section so that the nozzle will set at an angle to the tube to project a jet of steam at an angle. The jet nozzle is turned to project the steam in any desired direction, by means of a rod 27 having a loose connection at its lower end with the nozzle and in extending upward through the tube section 23 and outward through the swivel head 24 which also forms an elbow for connecting the sections 22 and 23. The outer end of the rod 27 is provided with a crank handle 28 by means of which the rod is turned to turn the jet nozzle. When not in use the tube section 22 is swung upward turning upon the longitudinal axis of the branch 21, into the position shown in dotted lines in Fig. 1 and the tube section 23 is permitted to hang downward alongside of the wall where it will be out of the way. This hanging nozzle is brought into operative position by turning the tube section 22 downward to bring its lower end opposite the opening 16 at the same time projecting the section 23 through the opening and downward between the rows of boiler tubes. A brace or laterally extending arm 29 is adjustably secured to the head or fitting 24 to engage the lower side of the opening 16 in the wall and hold the nozzle in operative position. When so inserted and the steam

turned on, every part of the lower ends of the boiler tubes at one side of the wall 5 and the top of the mud drum may be thoroughly cleaned by the jet of steam issuing through the jet nozzle which is turned by means of the handle 28 to direct the steam into every part of the lower end of the boiler setting. The same construction of hanging nozzle may be applied to the rear side of the boiler setting in a position to be projected through the opening 17 in order that the space at the rear side of the baffle wall may be cleaned when there are no openings at the rear side of the setting near the top of the drum.

A short vertical pipe 30 extends upward from the fitting 20 and is attached thereto by a suitable swivel connection and a tubular section 31 is connected thereto by an elbow and extends laterally therefrom. This tubular section 31 is of sufficient length to extend to a point opposite either of two openings 32 in the wall of the boiler setting, said openings being arranged substantially one-quarter of the way around toward each side from the front center line to the wall. The outer end of this tube section 31 is turned upwardly and mounted upon this upturned end is a fitting 33 carrying an extension tube 34 adapted to project through the opening in the wall. The inner end of the extension 34 is provided with a head 35 forming a jet nozzle to project steam across the boiler tubes opposite said opening. The fitting 33 is so attached to the tube 31 that it may be turned freely thereon and thus the extension 34 may be swung from side to side within the opening or turned to engage the similar opening at the opposite side of the wall when the tube 31 is swung around to bring it opposite said opening. The upper ends of the boiler tubes may thus be blown through the annular openings 32 which are sometimes provided in boiler settings of the vertical type.

Obviously parts of the blower as shown may be omitted in accordance with the construction of the separate boiler setting to which it is attached and changes may be made in the details of construction without departing from the spirit of my invention. I therefore do not wish to limit myself to the particular construction and arrangement shown.

Having thus fully described my invention what I claim is:

1. In a blower for boilers, the combination with a supply pipe, of a tube section pivotally connected to said pipe to swing upon a horizontal axis, a second tube section pivotally connected to the end of the first section to turn upon an axis extending transversely to the longitudinal axis of the first tube section, and a tubular extension or nozzle section carried by the second section.
2. In a blower for boilers, the combina- 130

tion with a supply pipe, of a tube section pivotally attached to the supply pipe to swing upon an axis extending transversely of the tubes of the boiler toward and from an opening in the boiler setting, a second tube section pivotally attached to the opposite end of said first section to turn to a position parallel therewith and to project into said opening, and means carried by said second section to direct a jet of steam across the boiler tubes.

3. In a blower for boilers, the combination with a supply pipe, a tube section pivotally attached at one end to said supply pipe to swing upon an axis extending transversely of the tubes of said boiler to bring its opposite end opposite an opening in the wall of the boiler setting and to turn upon an axis extending longitudinally of said boiler tubes to change its position relative to said supply pipe and bring it in position before a second opening in said wall, and a tube section pivotally attached to the end of the first tube section to turn at an angle thereto and project into said openings.

4. In combination with a boiler setting having two openings in the wall thereof, of a supply pipe, a tube section pivotally attached to said pipe midway between said openings to swing from one opening to the other, and a second tube section pivotally attached to the end of the first section to project into said openings.

5. In combination with a boiler setting having two openings in the wall thereof, of a supply pipe, a tube section pivotally attached at one end to said supply pipe midway between said openings to swing from one to the other of said openings, a second tube section pivotally attached to the end of the first section to turn thereon upon an axis extending at right angles to the longitudinal axis of said tube to project into said openings, and a member carried by said second section for directing jets across the tubes of the boiler.

6. In combination with a boiler setting having an opening therein, of a supply pipe above said opening, a tube section pivotally attached at one end to said pipe to turn downward with its lower end opposite said opening, a second tube section pivotally attached to the lower end of the first section to be turned into parallelism therewith and to project into said opening, a jet nozzle carried by the second section, and means extending through said second section for turning said nozzle.

7. The combination with a boiler setting having openings therein and an opening midway between said openings and below the plane thereof, of a supply pipe, a tubular section pivotally attached to the supply pipe to turn in a horizontal plane from one to the other of said openings, a tubular section pivotally attached to the end of the first named section to swing in a horizontal plane and adapted to be projected through said openings, a vertically swinging tube section pivotally attached to the supply pipe to swing with its opposite end adjacent to the intermediate opening in the wall, and a tube section pivotally attached to the vertically swinging section to swing in a vertical plane and adapted to be projected through said opening.

8. In combination with a boiler setting having a circular wall and openings in the wall near its lower end and in its side, of a supply pipe extending upwardly adjacent to one side of said wall, a branch supply pipe extending laterally from said pipe to a point adjacent to the opening in the side of the wall, a plurality of tube sections articulated together and attached to the supply pipe to turn upon both and horizontally upon a vertical axis, one of said tube sections being adapted to be turned and projected through the openings at the bottom of the wall, a plurality of tube sections articulated together and attached to the branch pipe to turn in horizontal planes, one of said sections being adapted to be turned and projected through the upper openings in the wall of the boiler setting, and a plurality of tube sections articulated together and attached to said branch pipe to turn in vertical planes, one of said sections being adapted to be turned and projected through an opening in the wall of the boiler setting.

9. In combination with a boiler setting having an opening in one side, of a supply pipe extending above said opening, a plurality of tube sections articulated together and to said pipe to turn in vertical planes, one of said sections being adapted to be turned and projected through the opening in the wall of the boiler setting, a jet nozzle carried by said section and manually operable means for turning said nozzles.

In testimony whereof I affix my signature in presence of two witnesses.

THOMAS S. WALLER.
